UNITED STATES PATENT OFFICE.

ALONZO G. DUNNUCK, OF CONCORDIA, KANSAS.

ROAD-WORKING MACHINE.

1,308,174.

Specification of Letters Patent.

Patented July 1, 1919.

Application filed August 30, 1917. Serial No. 189,019.

To all whom it may concern:

Be it known that I, ALONZO G. DUNNUCK, a citizen of the United States, residing at Concordia, in the county of Cloud, State of Kansas, have invented certain new and useful Improvements in Road-Working Machines, of which the following is a full and exact specification.

The present invention relates to road-working machinery, and aims to provide an improved arrangement and construction of apparatus for grading the surface of road-beds. Accordingly, one of the objects of the invention is to devise a machine of this character having a road grading member arranged and supported in a novel manner for adapting the same to be presented in the proper relation to the road surface and also readily and conveniently adjusted with relation to said surface. To this end the invention provides a road grading member which is pivotally supported intermediate its ends, together with suitable adjusting means for varying the position of the grading member angularly with reference to its supporting connection as well as to the surface of the roadbed.

It is also sought to devise a construction wherein provision will be made for holding the grading member yieldingly in engagement with the surface being graded.

With these general objects in view, as well as minor objects as will appear in the course of the detailed description, the invention will now be described with reference to the accompanying drawings illustrating one form of construction which has been found to be practical and efficient, after which those features and combinations deemed to be novel will be severally set forth and defined in the appended claims.

In the drawings—

Figure 1 is a side elevation of a road working machine constructed in accordance with the present invention;

Fig. 2 is a plan view of the same;

Fig. 3 is a rear elevation of the machine;

Figs. 4 and 5 are detail sectional views taken on the lines IV—IV and V—V, respectively, of Fig. 2;

Fig. 6 is a detail sectional view, taken on the line VI—VI of Fig. 3; and

Fig. 7 is a detail section taken on the line VII—VII of Fig. 1.

Referring to the drawings in detail, these

illustrate the main machine frame as comprising the longitudinal forwardly converging members 2, the rear ends of which are connected to the arched yoke 4 provided with the supporting wheels 6; intermediate their ends these members 2 are joined by the transverse member 8 which supports the driver's seat 10, and the front ends of said members 2 are connected by a bracket plate 12 which is formed with a bearing 14 (see Figs. 4 and 5) for receiving the vertical pivot stem 16 projecting up from the yoke 18 of the caster wheel 20.

The road working member of the machine comprises a grading or scraping member or blade 22 which is carried by the lower edge of a beam 24 in diagonal relation to the road bed 26. The grading member is pivotally supported intermediate its ends, and preferably at a point nearer to the left end (relative to the direction of travel) of said member in order that the same, when suspended by its supporting means, will tend normally to assume a somewhat tilted position with its right end remaining in engagement with the surface of the road. At this intermediate portion of the grading member a bracket plate 28 is secured to the rear face of the beam 24 by means of bolts or the like 30. A pair of lugs 32 are formed on the lower end of said bracket plate 28 for carrying a bolt 34 to which is loosely pivoted the depending portions of a hanger arm 36. The forward end of the hanger arm 36 is received within a recess 38 on the bracket plate 12 to which the arm is pivoted by means of a bolt 40 carrying spacing washers 42 on the opposite sides of said arm 36. At the bend in the hanger arm 36 an angle plate 44 is secured to the arm, with which plate 44 is slidingly engaged a rod 46 connected at its upper end to an operating lever 48. This lever is pivotally mounted on a bracket 50 and provided with a latch 52 for engagement with a notched sector 54 formed on the bracket 50. Said bracket 50 is carried by the transverse member 8 in position for operation of the lever 48 from the driver's seat 10. Surrounding the rod 46 is a coil spring 56 in engagement at its opposite ends with the lever 48 and the angle plate 44 so that the forward operation of the lever will operate to depress the grading member in yielding engagement with the surface of the road, while the re-

verse operation of said lever will act to positively and bodily elevate the grading member either partially or completely out of contact with the road surface. For steady-
5 ing the movements of the grading member from the rear, a stay member 58 is provided which is loosely pivoted to a lug 60 intermediate the ends of the bracket 28, the rear end of said stay member being connected
10 pivotally to the yoke 4 adjacent to one of the wheels 6.

Means is provided for tilting the grading member transversely about its bolt connection 34 with the hanger arm 36, this being
15 for the purpose of varying the scraping or grading angle at which the blade 22 is presented to the road surface. This tilting means comprises a link 62 connected at one end to an ear 64 formed on the upper end
20 of the bracket plate 28, and at its other end to a lever 66 which is pivotally mounted on a bracket 68 secured to the hanger arm 36 in advance of the plate 44. The lever 66 is provided with a latch 70 coöperating with
25 a notched sector 72 formed on said bracket 68 for holding the lever 66 in various positions.

Means is also provided for longitudinally tilting the grading member for varying the angle at which it extends diagonally with reference to the roadbed. This means comprises an angular arm 74 pivoted at one end to a bracket 76 secured to the rear face of the beam 24 near its lower edge and in the
35 vicinity of its right end, the other end of said arm 74 being pivotally connected to one end of a rocking arm 78 pivoted at 80 to the right frame member 2; the other end of said rocking arm 78 is connected by a
40 link 82 to a lever 84 mounted on a bracket 86 carried by the left frame member 2, the said lever 84 being provided with a latch 88 coöperating with a notched sector 90 formed on the bracket 86 for holding said lever in set position.

There is also provided means for longitudinally tipping the grading member by raising its left end thereby tipping the grading member about its right end as a fulcrum. This tipping means comprises a lever 92 fulcrumed in a sleeve 94 secured to the left frame member 2. The outer end of this lever 92 has a straight portion 96 adapted for sliding engagement with an elongated loop 98 secured to the beam 24 adjacent its left end portion,—this sliding engagement being for the purpose of accommodating the other adjustments of the grading member. The inner end of the lever 92 is formed with a foot-engaging portion 100 extending in position for convenient operation by the foot of the driver when occupying the seat 10.

The draft connections provided for use
65 with the machine are arranged to include

draft equalizer mechanism of the general type illustrated in Letters Patent No. 1154104 issued to me on September 21, 1915. In assembling these draft connections in the present construction, the central cross-bar 70 102 of the equalizer mechanism is mounted for pivotal movement about the stem 16 of the caster wheel 20, while the outer members 104 of said equalizer mechanism are provided with the rigid stay members or 75 draft links 106 pivotally connected by bolts 108 or the like to the side frame members 2. A tongue or pole 110 is connected by means of a pivot bolt 112 to a casting 114 which is likewise pivoted about the axis of 80 the stem 16 by being journaled on the bearing 14 of said stem 16, as illustrated in Figs. 4 and 5. The pole may be locked in straight-ahead position, whenever desired, by means of a removable pin 116 extending through 85 registering openings in the casting 114 and the bracket plate 12.

It is found that a machine constructed in accordance with the foregoing operates very efficiently and satisfactorily to perform the 90 required functions of a road grading or scraping apparatus, the arrangement and construction being such as to greatly facilitate the necessary adjustments of the scraping or grading member and maintain 95 the same in the desired positions of adjustment. When desired the grading member may be set in the position shown in Fig. 3 with said member operating to grade uniformly throughout its length; or if it should 100 be found advisable to raise the left end of the grading member up slightly above the road surface (as when it is desired to allow the loose material to pass under the grading member at some intermediate portion so as 105 to fill depressions in the roadbed) this may be readily and quickly done by the operation of the foot lever 92, thereby lifting the left end portion of the grading member while leaving its right end portion in working 110 engagement with the roadbed. The effective working angle of the grading member with reference to the road surface is conveniently altered by operation of the lever 66, thereby tilting the grading member 115 transversely in an obvious manner. This lever and its connections are carried by the pivoted hanger arm 36 and in the vicinity of the middle portion of the grading member, and are thus arranged and adapted to 120 operate in the most effective manner for accomplishing their proper function while maintaining any desired adjustment of the grading member constant during any of the operations of the other adjusting means. 125 The particular angle of the diagonal relation of the grading member to the roadbed is adapted to be quickly and conveniently varied by the operation of the lever 84 to pull the right end portion of the grading 130

- member backward or forward the required extent, thus swinging the grading member angularly about its pivotal supporting connection 34, during which movement the 5 loop 98 simply slides freely over the straight portion 96 of the lever 92 so that the longitudinally vertically tilted relation of the grading member remains unchanged during the operation of said lever 84. When the 10 lever 48 is depressed to maintain the grading member in more or less effective engagement with the roadbed, the spring element 56 introduces a yielding action, so that the grading member may be allowed 15 to yield to a certain extent upon encountering any unusual obstructions in the roadbed. This spring 56 is inactive whenever the lever 48 is thrown to the rear for the purpose of raising the grading member, so 20 that the action in the raising of the grading member by the lever is positive, and by a sufficient throw of the lever the grading member may be bodily lifted on its pivotal supporting means completely out of contact 25 with the surface of the road. By locating the pivotal bolt 34 slightly to the left of the middle of the grading member, however, the grading member tends to assume the correct normal position, that is, to maintain its right end at the lower level, as is usual in road grading. In carrying out the various adjustments it will be understood 30 that all the connections with the grading member are sufficiently loose to accommodate all necessary relative movement in effecting said adjustments (see Figs. 6 and 7). The manner of applying the draft equalizer mechanism to the front end of the machine with the main axis of said mechanism coinciding with the vertical axis of the caster 35 wheel affords an efficient draft arrangement and a novel and simple combination of the elements entering into said caster wheel and draft connections.
- 45 It will thus be apparent that a simple, efficient and comparatively inexpensive arrangement and construction have been provided for carrying out the desired objects of the invention, and while the preferred form of construction has been illustrated, the right is reserved to such formal changes or modifications as may fairly fall within the scope of the appended claims.
- What I claim is:
- 50 1. A road-working machine comprising a wheeled frame, a draft arm pivotally carried by said frame, a grading member supported near its midpoint from said draft arm and provided with a loose pivotal con-
- nection thereto permitting independent vertical movement of the opposite ends of said grading member with reference to said pivotal connection, and yielding means associated with said draft arm and exerting a downward pressure thereon for holding said 60 grading member in resilient engagement with the road surface.
2. A road-working machine comprising a wheeled frame, a draft arm pivotally carried by said frame, a grading member connected near its mid-point with said draft arm, a lever carried by said frame and connected to said draft arm and operable to raise and lower the same for bodily shifting said grading member into and out of operative position, and yielding means associated with said lever for exerting a downward pressure on said draft arm and grading member, said grading member having a loose pivotal connection with said draft arm 70 permitting independent vertical movement of the opposite ends of said grading member about said pivotal connection.
3. A road-working machine comprising a wheeled frame, a draft arm pivotally carried by said frame, a grading member connected near its mid-point with said draft arm, a lever carried by said frame and connected to said draft arm and operable to raise and lower the same for bodily shifting 75 said grading member into and out of operative position, yielding means associated with said lever for exerting a downward pressure on said draft arm and grading member, said grading member having a loose pivotal connection with the draft arm permitting independent vertical movement of the opposite ends of said grading member about said pivotal connection, and means connected with one end of said grading member for 80 longitudinally tipping said member in a vertical direction in opposition to said yielding means.
4. A road working machine comprising a wheeled frame, a draft arm pivotally carried by said frame, a grading member pivotally supported intermediate its ends by said draft arm, a bracket projecting laterally from said draft arm, a lever carried by said frame and provided with a rod pivoted to 85 said lever and slidably engaging said bracket, and a spring coiled about said rod and abutting at its opposite ends against said bracket and the end of said lever, respectively.
- 90 In witness whereof I hereto affix my signature.
- ALONZO G. DUNNUCK.
